METHOD AND APPARATUS FOR TREATING SHEETS

Nathaniel B. Ornitz, Pittsburgh, Pa., assignor to National Alloy Steel Company, Blawnox, Pa., a corporation of Pennsylvania

Application May 19, 1930, Serial No. 453,482

1 Claim. (Cl. 263—6)

My invention relates to the heat-treating or annealing of sheets and, in particular, contemplates a novel method and apparatus for conveying the sheets through an annealing furnace.

5 It has been found that the steel rolls forming the conveyors now used for passing sheets through an annealing furnace tend to collect coats of oxide which are rough and pointed so that sheets passing thereover become scratched and dented. Such sheets, of course, are not perfect and must be scrapped or given an inferior grade by the inspector. In some instances, it has been the practice to place a perfect sheet on top of an imperfect sheet resting on the conveyor 10 rolls. The top sheet is thus protected to some extent from abrasion by the rolls, although, in many instances, the upper sheet is dented through the lower one by the projections from the conveyor rolls.

15 20 When the rolls reach this stage of oxide coating, it is necessary to shut down the furnace until the rolls can be polished by grinders. This shutting-down is a long process and is a serious curtailment to the production of the furnace. A 25 period of several days is necessary for cooling the furnace and further time is required for the actual polishing of the rolls before the furnace can again be placed in service.

25 I have invented a method and means for passing sheets through an annealing furnace which avoids the objections above-mentioned. According to the invention, I employ a conveyor having supporting elements formed of refractory or non-oxidizable material such as silicon carbide. Such 30 surfaces do not tend to form any oxide coat which would mar the finish of the sheets passing through the furnace. In addition, the problem of localized chilling, which has been met with heretofore, is solved by this construction.

35 40 For a complete understanding of the invention, reference is made to the accompanying drawing in which,

Figure 1 is a partial side elevation of a conveyor constituting a present preferred embodiment of the invention;

Figure 2 is an end elevation;

Figure 3 is a top plan view of the portion of the apparatus shown in Figure 1; and

Figure 4 is a partial side elevation of a furnace having a modified form of conveyor therein. Referring in detail to the drawing, I provide a conveyor composed of a plurality of carriers such as that shown at 10. The carrier 10 comprises a central vertical web portion 11, a bottom link portion 12, and a top supporting portion 13. The bottom portion 12 of the carrier is connected, as, for instance, by links 14 and 15, to similar carriers adjacent that shown at 10. A number of such carriers linked together form a continuous conveyor passing through the annealing fur-

nace, the floor of which is indicated schematically at 16. The conveyor may be driven by any convenient source of power. The web portions 11 of the carriers 10 ride in a slot 17 in the floor of the furnace and the links 14 and 15 and 65 the bottom portions of the carriers pass through a channel 18 connecting with the slot.

The top portion of the carrier is provided with four projecting arms 19, 20, 21, and 22. At their outer ends, these arms support pads 23 having 70 dovetailed slots 24 therein. Refractory inserts 25, which may be of any suitable material such as silicon carbide, have dovetailed projections 26 fitting into the slots 24. The inserts 25 afford a series of spaced refractory supports for sheets 75 being conveyed through the furnace. Any suitable non-oxidizing material may be used for the supporting inserts 25.

In operation, the conveyor is driven continuously and the sheets are placed individually on 80 the carriers and so pass through the furnace. No oxide coat forms on the refractory inserts 25 to scratch or dent the surface of the sheets. Since there is no relative movement between the supporting surface and the sheet in this type of 85 conveyor, the latter is without a mark or blemish when taken from the delivery end of the furnace. Because of the thermal qualities of the insert, no localized chilling occurs and the finished sheet is uniformly treated throughout its 90 area.

A modified form of the invention is illustrated in Figure 4. According to this modification, a roller conveyor is constituted by a plurality of 95 rolls 30. The rolls 30 are provided with refractory inserts 31 similar to those shown at 25 in the first form of the invention. The inserts 31, of course, are curved to conform to the surface of the roll 30. The advantages resulting from the preferred form of the invention are also inherent 100 in the modified form shown in Figure 4.

Although I have illustrated and described but two embodiments of the invention, the scope thereof is not limited to the specific details of these modifications. Any changes may be made 105 in the construction without departing from the spirit of the invention as set forth in the appended claim.

I claim:

In a conveyor for passing metallic sheets 110 through an annealing furnace, a plurality of linked carriers having vertical webs and horizontally extended arms, and a silicon carbide insert on each of said arms for supporting the sheets.

NATHANIEL B. ORNITZ.
